US00D900405S

(12) **United States Design Patent** (10) Patent No.: **US D900,405 S**
Stevens et al. (45) Date of Patent: **** Oct. 27, 2020**

(54) **PROTECTIVE MASK**(71) Applicant: **GI SPORTZ DIRECT LLC**, Sewell, NJ (US)(72) Inventors: **Simon Benjamin Stevens**, Barnsboro, NJ (US); **Bryan Stowe**, Sewell, NJ (US)(73) Assignee: **GI SPORTZ DIRECT LLC**, Sewell, NJ (US)(**) Term: **15 Years**(21) Appl. No.: **29/623,659**(22) Filed: **Oct. 26, 2017****Related U.S. Application Data**

(60) Continuation of application No. 29/488,569, filed on Apr. 21, 2014, now Pat. No. Des. 801,589, which is a continuation-in-part of application No. 29/370,432, filed on Jun. 14, 2010, now Pat. No. Des. 703,388, which is a continuation of application No. 29/327,424, filed on Nov. 5, 2008, which is a division of application No. 29/253,707, filed on Feb. 10, 2006, now Pat. No. Des. 589,211.

OTHER PUBLICATIONS Vforce, Mask Care and Use Instructions (in U.S. Appl. No. 29/253,707).
Vforce, Mask Manual (in U.S. Appl. No. 29/253,707).*Primary Examiner* — Michael A. Pratt*(74) Attorney, Agent, or Firm* — Volpe Koenig**(57) CLAIM**

The ornamental design for a protective mask, as shown and described.

DESCRIPTIONFIG. 1 is a front perspective view of an embodiment of a protective mask according to our invention;
FIG. 2 is a front elevational view of the design shown in FIG. 1;FIG. 3 is a right side elevational view of the design shown in FIG. 1, the left side being a mirror image thereof;
FIG. 4 is a top plan view of the design shown in FIG. 1; and,
FIG. 5 is a bottom view of the design shown in FIG. 1.
All broken lines appearing in the drawings form no part of the claimed design.**1 Claim, 4 Drawing Sheets**US D900,405 S
